UNITED STATES PATENT OFFICE.

BENOIT GUERRY, OF GARRISON, NEW YORK.

PUZZLE-BOX.

933,432.

Specification of Letters Patent.

Patented Sept. 7, 1909.

Application filed February 8, 1909. Serial No. 476,620.

To all whom it may concern:

Be it known that I, BENOIT GUERRY, a citizen of the Republic of France, having declared my intention of becoming a citizen 5 of the United States, residing at Garrison, Putnam county, and State of New York, have invented certain new and useful Improvements in Puzzle-Boxes, of which the following is a specification.

10 My improvements relate to boxes which can only be opened in a particular manner by the manipulation of the cover when the box is reversed in position, and the invention consists in the specific construction and arrangement of parts hereinafter described and claimed.

In the accompanying drawings, Figure 1, is a top view of my improved puzzle box; Fig. 2, a central longitudinal section on plane 20 of line 2—2—Fig. 1; Fig. 3, a top view of the box open, parts being broken away; Fig. 4, a transverse section upon plane of line 4—4—Fig. 1; Fig. 5, is a view similar to Fig. 2, the device being inverted; Fig. 6, a 25 detail view of the underside of the outer end of the main cover.

The main cover C, is pivotally connected to one end of the box B by means of the pin a, the other end of the box being formed 30 with a retaining projection a', and flange a², for the reception and retention of the other end of the cover, which latter is formed with the recess c, the sides of which fit over and engage the projection a', while 35 the edge c', fits under the flange a². The pivoted end of the main cover is formed with the slot c², through which the pivot a, projects, so as to allow of the necessary movement of the cover when it is opened or 40 closed, in order to clear or engage with the detaining projection a'.

S, is a supplemental cover section fulcrumed on the pivot a, on which it turns but has no play or looseness being unlike the 45 cover C, in which provision is made for longitudinal movement by the slot c², as before stated. The lower part of the pivot a, is embedded in the box B, and its upper portion is embedded in the supplemental 50 cover S, which is made of two layers or plates s, s', so as to cover the upper end of the pivot a, and render it invisible.

The inner end s², of the plate s, is at an angle considered transversely to fit a correspondingly inclined edge d on the cover C. 55 The plate s, is also formed with a hole h,

which, when the supplemental cover S is in a closed position over the main cover C, coincides with a recess r, in the superstructure of the main cover C. Said recess r, contains 60 a bolt b, which, when the cover is uppermost, falls into the hole h, in the supplemental cover S, and locks the main cover C, and the supplementary cover S, together. When however the box is reversed, with the cover 65 underneath, the bolt b, falls back into the recess r, and the supplemental cover S may be turned laterally away from the main cover C, provided the slide e, on the superstructure of the main cover has been withdrawn. This slide e, is held to the superstructure of the main cover by flanges e' e', 70 and a stop e², which rests in a slot e³ in said slide, thus providing for the longitudinal movement of the slide e. The ends e⁴, e⁴ of 75 the flanges e', e', when the slide is closed, engage with corresponding ends s⁵, s⁵ of flanges on the supplemental cover S, and thereby prevent the turning of the latter on the pivot a, until the slide e, is drawn out- 80 ward.

Supposing the box to be closed, to open it, it is reversed with the cover underneath, in which position the bolt b, drops into the recess r, and away from the hole h, in the 85 supplemental cover S. The slide e, being then or previously drawn outward, the supplemental cover S may be turned upon the pivot a. This releases the main cover, so that it may be slid back away from the retaining shoulder a'. When the open box is turned upward, the bolt b, drops down and prevents the closing of the supplemental cover S, until the box is again reversed, so that the bolt drops back into the recess r, 90 when the parts may be readily restored to the relative positions above described. 95

F is a fake slide on the supplemental cover S, corresponding to, and opposed to the slide e, on the superstructure of the cover. 100 Its object is simply to confuse the uninformed manipulator of the box cover, and it performs no other function.

The box and cover thus constructed and arranged form an effective puzzle device 105 which may be used not only for amusement but to effectually prevent access to the contents of the box to all but those intrusted with the secret method of opening the same.

What I claim as my invention and desire 110 to secure by Letters Patent is,

A puzzle box B having at one end the re-

taining projection a' and flange a^2 , and at the other end the upwardly extending pivot a , the main cover C, formed with recess c at one end for engaging the projection a' and with the longitudinal slot c^2 at the other end, along which the pivot is adapted to move, also formed with a recess r , the bolt b , slideable in said recess, and the supplemental cover S above a portion of the main cover

adapted to turn at one end on the pivot a 10 and having at the other end a hole h , registering with the recess r when the covers are in position to close the box.

BENOIT GUERRY.
